UNITED STATES PATENT OFFICE

RICHARD M. CRAIG, OF SAN ANTONIO, TEXAS

DISPLAY MECHANISM

Application filed October 15, 1929. Serial No. 399,804.

This invention is an apparatus whereby an optical illusion will be produced to attract attention and, while the apparatus is intended primarily for use in the advertising field, it may be advantageously employed for demonstrations in a class room as an aid to instruction in geometry, physics and optics. In the preferred embodiment of the invention, a plurality of lights are mounted upon a rotatable carrier which, in turn, is carried by an arm rotating about a fixed center of motion so that there is a planetary movement of the lights whereby an infinite variety of geometrical designs are produced. The light-carrying arms are preferably rotated about a common center in a direction opposite to the direction of rotation of the member upon which they are mounted and at constantly varying speeds, the result being that a very great variety of designs appear and they attract and hold the attention of the observer so that the apparatus is admirably adapted for advertising. The invention is illustrated in the accompanying drawings and will be hereinafter fully set forth and defined.

In the drawings:

Figure 1 is a view, partly in side elevation and partly in longitudinal section, of the preferred embodiment of the invention,

Fig. 2 is a front elevation of the same,

Fig. 3 is an enlarged detail sectional elevation of a belt shifting mechanism,

Figs. 4, 5, 6, 7 and 8 are diagrammatic views illustrating, in a general way, some of the designs which are produced by the apparatus, and

Fig. 9 is a diagrammatic view of a modification.

In the embodiment of the invention illustrated in Figs. 1 and 2, there is employed a base plate 1 which may be of any suitable durable material which will furnish a steady support for the parts mounted thereon. Secured upon the base is a hollow frame or standard 2 having a bearing block 3 at its upper end, which bearing block has a reduced extension 4 on its front side. Rotatably mounted in and extending through the bearing block 3 and its extension 4 is a hollow shaft 5 which is equipped at its rear end with a pulley 6 and a larger pulley 7, the latter being operatively connected by a belt 8 with a pulley 9 upon the drive shaft of an electric motor 10. The motor 10 is secured upon the base 1 at the rear of the frame 2 and the pulleys 7 and 9 have such relative diameter that they constitute an effective speed-reducing gear. At an intermediate point in the height of the hollow frame 2, a shaft 11 is journaled in the front and rear walls thereof and upon said shaft is secured an elongated cone pulley 12, while upon the rear extremity of the shaft is a pulley 13, operatively connected by a belt 14 with the pulley 6 on the hollow shaft 5, and a spur gear 15, meshing with a larger spur gear 16 on the rear end of a shaft 17 which is also journaled in the front and rear walls of the frame 2 below the cone pulley 12, as shown in Fig. 1. Below the shaft 17, a third shaft 18 is journaled in the front and rear walls of the hollow frame 2 and said shaft carries a cone pulley 19 which is of the same form as the pulley 12 but reversed relative thereto, and about the cone pulleys is trained a belt 20, as shown in Fig. 1 and as will be understood. At the larger end of the cone 19, a disk or ring 21 is loosely mounted upon the shaft 18 and has an external diameter which causes its periphery to lie flush with the periphery of the cone pulley 19, the purpose of this loosely mounted member being more fully set forth hereinafter. On the front end of the shaft 18 is secured a pulley 22 about which is trained a crossed belt 23, as clearly shown in Figs. 1 and 2. The shaft 17 is constructed between the front and rear walls of the frame 2 with a sleeve or enlarged body fixed to the shaft and having a double spiral groove 24 formed in its circumference and extending from end to end thereof, the branches of the groove being connected adjacent the ends of the body by branches 25 which extend across the circumference parallel with the ends of the body so that an element traveling in the spiral grooves will be transferred from the spiral in one direction to the spiral running in the opposite direction and the direction of travel of said element, consequently, reversed. Secured in the frame adjacent

and parallel with the shaft 17 is a guide rod 26 and upon said rod is mounted a slide 27 which is formed with a sleeve or hub portion 28 encircling the spirally grooved body. The slide is vertically grooved or bifurcated, as shown at 29, so that it may fit around the belt 20 and, therefore, shift the belt along the cone pulleys as the slide travels along the rod 26 and the spirally grooved actuating body. Mounted in the slide at the side opposite the guide rod is a plug or dog 30 which enters the groove 24, as clearly shown in Fig. 3, so that as the shaft 17 and the grooved body thereon rotate, the slide will be caused to travel longitudinally thereof.

Secured upon the front end of the hollow shaft 5 is an arm 31 provided with a counter-weight 32 at one end and formed at its opposite end with a bearing sleeve 33 in which is mounted a shaft 34 having a pulley 35 secured upon its rear end, said pulley having a belt 36 trained thereover. Rotatably mounted upon the extension 4 of the bearing block 3 is a double pulley 37 and in one groove of this double pulley the belt 36 runs while in the other groove the belt 23 is trained. A circular body 38 of insulation is secured upon the front end of the shaft 34 and a conductor ring 39 is embedded in said body. A display member 40 is secured upon the front extremity of the shaft 34 and securing nuts 41 are fitted upon the shaft in such manner that the insulated body 38 and the display member 40 will be held in spaced relation and the insulated body will bear against the front end of the bearing sleeve 33 so that endwise movement of the shaft 34 in the bearing sleeve will be prevented by said body and by the pulley 35.

In the particular embodiment of the invention shown in the drawings, the display member consists of five radial arms which may be integrally formed or otherwise rigidly connected together in proper angular spaced relation, and upon each of said arms is a plurality of electric lamps 42, three lamps being shown in the present instance. These lamps may be of any size and preferably will be variously colored, although they may all be of the same color and the number of the lamps as well as the number and size of the arms upon which they are mounted may be varied at will. The best effects are attained in the small portable signs by using small 10-watt lamps, but in the larger apparatus intended for outdoor advertising purposes the ordinary bulbs may be used. It may also be noted that, while I prefer to use electric lamps and the best effects are attained by said means, the purposes of the apparatus may be served by employing phosphorescent or luminescent paint and forming spots or other designs at intervals upon the radial arms.

The conductor ring 39 is in constant con-

tact with a brush 43 secured upon a block 44 of insulation which is carried by the front side of the arm 31 and from the said brush a cable 45 extends into the hollow shaft 5 and then through said shaft to an opening 46 therein through which it is carried to be secured to a conductor ring 47 which is fixed upon a ring or collar 48 of insulation which encircles the shaft and is secured thereto. A brush 49 is in constant contact with the conductor ring 47 and is carried by a block 50 of insulation secured upon the bearing block 3, as clearly shown in Fig. 1, an input cable 51 having one branch secured to the brush and its return branch grounded upon the frame of the machine. From the conductor ring 39, wires 52 extend through the insulation 38 and then out to the several lamps 42 to activate the same, the return terminals of the several lamps being grounded upon the radial arms so that there will be a grounded return for the circuit. If preferred, however, the several lamps may have return wires led into a cable extending through the shaft so as to make a metallic return.

In employing the apparatus for advertising purposes, a sign member 53 is supported in any convenient manner concentric with the main shaft 5 and the diameter of this sign member should be such that the circle defined by said member will approximately coincide with the outermost circle described by the design-forming elements as they are carried around the shaft 5 as a center. This sign member may be a painted transparency and is illustrated in the drawings as a box having a glazed front 54 and containing a plurality of electric lamps 55. Any desired announcement may be painted upon the glazed front of the sign member or the announcement may be formed by arranging the lamps 55 in such a manner as to form letters and words or other characters. The lamps 55 are connected by wires 56 with a source of current and intermediate portions of the wires are carried to a switch mounted upon the rear wall of the frame 2 adjacent the guide rod 7, as shown in Fig. 3. This switch may be of any suitable form and is illustrated conventionally as comprising a fixed member 57 and a resiliently movable member 58 arranged in the path of the slide 27 so that, when the slide is at the extreme limit of its movement toward the right in Figs. 1 and 3, it will bear against said movable switch member and close the same against the fixed member and complete the circuits so that the lamps 55 will be illuminated.

The operation will, it is thought, be readily understood from the foregoing description, taken in connection with the accompanying drawings. When the motor is running, the shaft 5 will be rotated constantly in one direction and the arm 31 will, of

course, rotate in the same direction and at the same speed. From the shaft 5 motion is transmitted through the gearing shown and described to the shaft 17 and the upper cone 12 and from the upper cone is transmitted to the lower cone 19 by the belt 20. The shaft 17 and the grooved controlling body thereon will rotate at a relatively very low speed so that the slide 27 will travel slowly from end to end of the controlling body and thereby shift the belt 20 slowly from end to end of the cone pulleys. When the belt 20 is at the left hand end of the pulleys, the lower pulley 19 will be rotating at its maximum speed and as the belt travels toward the right the speed of said pulley will be gradually reduced. The rotation of the lower cone pulley and its shaft will be transmitted through the pulley 22 and belt 23 to the pulley 37 and from said pulley through the belt 36 and pulley 35 to the shaft 34 and the display member so that the display member will be rotated in a direction contrary to the direction of rotation of the arm 31 while at the same time it is caused to travel in an orbital path having the shaft 5 as its center because the shaft 34 is mounted in the end of the arm 31. The display member will, therefore, be driven at a constantly varying speed and because the speed of rotation of the design-making elements, whether they be electric lamps, mirrors or spots of luminescent paint, is higher than the speed of vision, the observer will not be able to detect the separate lamps or other elements but will apparently see circles and ellipses defined by the lamps, that is to say, the paths of the respective lamps will appear to be lines of light instead of lamps located successively at various points. It is not possible to illustrate the various designs which are formed by the display member during its rotation but, considering any one lamp of said member, the designs made will approximate those shown in Figs. 4 to 8, the design appearing in Fig. 4 being formed when the display member is rotating at its highest speed and as its speed reduces the design will successively change to those shown in Figs. 5, 6 and 7, while at its lowest speed the display member will form concentric circles, as shown in Fig. 8. When the belt 20 has been shifted to the extreme right hand end or base of the cone 19, it will pass onto the loosely mounted ring 21 and no independent rotation will be imparted to the shaft 34 and the display member, this condition continuing while the dog 30 is riding through the branch 25 of the double spiral groove. At this time the display member will rotate about the shaft 5 at the same speed as the arm 31 and will be describing concentric circles, indicated in Fig. 8. When the slide reaches its position at the extreme right, it will bear upon the switch 57, 58 and will energize the lamps 55 in the sign member so that the announcement on the sign will be visible and will appear to be framed by the circles described by the display member. When the slide reverses and starts on its forward travel, the belt 20 will be shifted from the ring 21 onto the cone 19 and the display member will again form constantly changing designs.

In Fig. 9, I have illustrated an arrangement by which the invention may be utilized to make a large display. The display member 59 is rotated about its own axis and about the axis of its carrier 60 in the same manner as the apparatus shown in Figs. 1 and 2 and previously described. Instead of electric lamps upon the display member, however, I provide mirrors 61 having the curvature of their surfaces carefully calculated and set at proper predetermined angles upon the display member. A large screen of any preferred type, indicated at 62, is provided in front of the display member and a spot-light 63 is placed in such position as to throw the rays therefrom onto the display member. The mirrors upon said member will, of course, reflect the light onto the screen and the various designs formed by the lights in the mirrors will be shown upon the screen. If a color wheel be interposed between the spotlight and the mirrors, an infinite variety of color combinations will be shown upon the screen together with the constantly varying designs.

I have stated that in the small portable apparatus I prefer to employ 10-watt bulbs and that the bulbs may be colored if desired and that in the large outdoor signs the ordinary standard bulbs may be used. It may be noted also that the lamps need not be all continuously lighted and the designs may be further varied and the attractiveness of the apparatus enhanced and the seeming mystery of its operation deepened by causing some of the lamps to flash intermittently. This result may be accomplished by inserting the ordinary well known commercial flasher buttons in the bases of some of the lamps or by interposing switches in the conductors leading to or from the lamps. If white light bulbs, such as are employed in automobile headlights, are employed, the bulbs will give points of light and the figures of the several designs will be drawn in sharp lines spaced widely apart. If ordinary Christmas tree lights of the cone-shaped type are used, the lines depicted in the several designs will be wider than those defined by the automobile bulbs and if the lamps be colored very beautiful effects will result. In using colored bulbs, the weaker colors will be placed nearer the center of the display member. As larger globes are used, the bands of action or lines defined in the design become wider and when the lights are colored the intersecting lines in the designs produce tartan or plaid effects. If small neon tubes be used, the lines defined by the several lamps are shown as lines made

up of dots. This is due to the fact that the Neon tubes operate only on alternating current and in actual fact are being constantly lighted and extinguished but when standing still this effect is not noticeable although when whirled it will give the appearance of dots, as stated. In very large signs, each lamp may be replaced by a group of lamps which will further mystify as to the effects produced.

Having thus described the invention, I claim:

1. Apparatus for the purpose set forth comprising a sign member, a carrier rotatably mounted concentric with the sign member, a display member rotatably mounted in one end of the carrier and arranged in front of the sign member, means for rotating the carrier at a constant speed, means for rotating the display member independently of the carrier at a constantly varying speed, and means for illuminating the sign member during the interval when the display member is rotating at its slowest speed.

2. Apparatus for the purpose set forth comprising a sign member, a carrier rotatably mounted concentric with the sign member, a display member rotatably mounted in one end of the carrier and arranged in front of the sign member, means for rotating the carrier at a constant speed, means for rotating the display member in a direction opposite the direction of rotation of the carrier and at a constantly varying speed, means for maintaining the speed of rotation of the display member at its lowest degree during an interval to permit change in the progression of speeds of the display member, and means for illuminating the sign member during said interval.

3. Apparatus for the purpose set forth comprising a main shaft, a carrier arm secured upon one end of the shaft, a display member rotatably mounted in one end of the carrier arm, means for rotating the main shaft, means driven by the main shaft for rotating the display member at a constantly varying speed and including relatively reversed cone pulleys, a belt trained about said pulleys, a rotatable body having a double spiral groove in its circumference extending from end to end thereof, and a slide carrying a dog engaged in said groove and having a forked portion engaging said belt.

4. Apparatus for the purpose set forth comprising a supporting frame, a bearing block in the upper end of the frame having a reduced extension on its front side, a main shaft journaled in and extending through said bearing block, a double pulley mounted on said extension, a carrier arm secured on the front end of said shaft, means for rotating the shaft at a constant speed, a display member having a shaft rotatably mounted in one end of the carrier arm, a pulley on the rear end of said shaft, a belt trained about

said pulley and about one side of the double pulley, a cone pulley driven from the main shaft, a second cone pulley reversed relative to the first-mentioned cone pulley, a belt trained about said cone pulley, a transmission pulley connected with the second-mentioned cone pulley, and a crossed belt trained about said pulley and one side of the double pulley.

5. Apparatus for the purpose set forth comprising a support, a bearing block at the upper end of the support, a main shaft journaled in and extending through said support, a carrier arm secured on the front end of said shaft means for rotating the shaft, a display member having a shaft journaled in one end of the carrier arm, a cone pulley driven by the main shaft, a second cone pulley reversed relative to the first-mentioned cone pulley, a loosely mounted ring immediately adjacent the larger end of the second-mentioned cone pulley, a belt trained about the cone pulleys, means driven from the main shaft for shifting the belt along the cone pulleys and periodically shifting it onto and from the loosely mounted ring, and means operatively connecting the second-mentioned cone pulley with the pulley on the display member shaft whereby the display member will be rotated at a constantly varying speed in a direction opposite to the direction of the rotation of the carrier arm and at intervals will be at rest with respect to the carrier arm.

6. Apparatus for the purpose set forth comprising a carrier rotating at a constant speed, a display member mounted eccentrically on the carrier, means to rotate the display member independently at a constantly varying speed whereby to produce constantly varying geometrical designs, means to arrest the independent rotation of the display member at intervals whereby it will describe concentric circles, a sign arranged to be framed by the circles, and means for illuminating the sign when it is so framed.

In testimony whereof I affix my signature.
RICHARD M. CRAIG. [L. S.]
